United States Patent Office

Des. 213,672
Patented Apr. 1, 1969

213,672

BOTTLE

Harry S. Dearling, 25 E. 83rd St.,
New York, N.Y. 10028

Filed Dec. 11, 1967, Ser. No. 9,736

Term of patent 14 years

Int. Cl. D9—01

U.S. Cl. D9—118

FIG. 1

FIG. 2

FIG. 3

FIG. 4

I claim:

The ornamental design for a bottle, as shown.
